UNITED STATES PATENT OFFICE.

JOHN J. WALLACE, OF MONTROSE, ILLINOIS.

DESIGN FOR A LINK FOR CLOTHES-LINES.

SPECIFICATION forming part of Design No. 19,685, dated March 4, 1890.

Application filed January 23, 1890. Serial No. 337,886. Term of patent 14 years.

To all whom it may concern:

Be it known that I, JOHN J. WALLACE, a citizen of the United States, residing at Montrose, in the county of Effingham and State of Illinois, have invented a new and original Design for Links for Clothes-Lines, of which the following is a specification.

The invention relates to a new and original design for links for clothes-lines.

10 In the drawings, Figure 1 is a side view of a clothes-line link showing my new design. Fig. 2 is a plan view.

15 The leading feature of my design is the rectangular insertion-opening having slightly-inclined sides.

Referring to the accompanying drawings, 1 designates a clothes-line link, having parallel side parts 2 and 3, and provided at its ends with loops or rings 4 and 5, which are arranged 20 at right angles to each other. The clothes-line link 1 is provided midway its length with

a rectangular opening 6, having parallel sides 7 and 8 and inclined ends 9 and 10, that are arranged at an angle to the sides 7.

Having described my invention, what I claim is—

The design for a clothes-line link herein shown and described, the same consisting of the parallel parts 2 and 3, having at their ends the rings 4 and 5, arranged at right angles to each other, and being provided midway its length with the rectangular opening 6, having the parallel sides 7 and 8 and the inclined ends 9 and 10, as set forth.

In testimony that I claim the foregoing as my own I have hereto affixed my signature in presence of two witnesses.

JOHN J. WALLACE.
